(57) **CLAIM**

The ornamental design for a multi-person enclosure pop-up tent, as shown and described.

DESCRIPTION

FIG. 1 is a front perspective view of a multi-person enclosure pop-up tent according to an embodiment of the present invention.

FIG. 2 is a front view of the pop-up tent shown in FIG. 1, the rear view being identical.

FIG. 3 is a left side view thereof, the right side view being identical.

FIG. 4 is a top view thereof.

FIG. 5 is a bottom view thereof.

FIG. 6 is a front perspective view of a multi-person enclosure pop-up tent according to a similar embodiment of the present invention, with an additional roof added to the pop-up tent.

FIG. 7 is a front view of the pop-up tent shown in FIG. 6, the rear view being identical.

FIG. 8 is a left side view thereof, the right side view being identical; and,

FIG. 9 is a top view thereof.

The broken lines shown in the drawings illustrate unclaimed stitching or portions of the multi-person enclosure pop-up tent that form no part of the claimed design.

The dash/broken lines form an unclaimed boundary of the design, or disclaimed elements such as stitching. Any elements shown in dash/broken lines form no part of the claimed invention in this application and are shown for environmental purposes only.
